UNITED STATES PATENT OFFICE.

SAGITO J. LEACH, OF ASHTABULA, OHIO, ASSIGNOR TO THE ASHTABULA BOW SOCKET COMPANY, OF ASHTABULA, OHIO, A CORPORATION OF OHIO.

TOP FOR VEHICLES AND THE LIKE.

Application filed November 10, 1921. Serial No. 514,204.

The present improvements, relate, as indicated, to vehicle tops, and particularly to the construction of the foldable outrigger or forwardly extending portion of so-called "one man" tops, which is the type at present largely in use on automobiles. In practically all these one man tops the outrigger bow, which extends horizontally in the open position of the top, is articulated, i. e., is connected, by means of swing arms, to the main bow or standard from which it is supported. In addition, such articulated outrigger bow usually carries one or more supplemental bows in order to support the top intermediate of the outrigger bow proper and such main bow or the back bow where the outrigger structure is supported from a standard that does not rise clear to the top.

The object of the present invention is to provide an outrigger structure of the character thus generally described which will be simple and easy to manufacture, compact when folded into a "stack", and rigid and substantial when extended. To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical forms in which the principle of the invention may be used.

In said annexed drawings:—

Fig. 1 is a side elevation of a top-supporting structure or frame embodying the present improvements, such top being adapted for, and shown as, being mounted on an automobile body or tonneau of the so-called roadster type; Fig. 2 is a similar side elevation on a slightly modified construction; Fig. 3 similarly illustrates the adaptation of my improved construction to a longer body or tonneau, in which, in addition to the main bow that operates the outrigger structure, a rear or back bow is employed; Fig. 4 similarly illustrates my improved construction of top as adapted to a longer body or tonneau in which but a single main bow or standard is employed, the latter inclining rearwardly so as to leave practically the entire side space clear of bows; Fig. 5 shows the adaptation of the construction shown in

Fig. 2 to a forwardly inclined main bow; and Fig. 6 is a side elevation on a somewhat larger scale of the rear portion of the outrigger structure of present interest, showing linkage and joints in detail.

While I have thus shown, and shall describe, my improved top as applied to an automobile body, it will be understood that it is equally adapted for use on motor boats or other vehicles, and that the number of main bows in addition to the one utilized to support the outrigger structure, as well as the number of supplemental bows carried by the latter, will depend upon the longitudinal extent of the vehicle body which is to be covered by the top. It will also be understood that the term "bow" is here used inclusively to designate, not merely the bow proper, whether of wood or metal, but also the metallic sockets or equivalent members that carry the same, these parts, when regarded in side elevation, constituting the equivalent of the so-called "sticks" in the all-wooden bow type of construction. It will accordingly be a matter of convenience to refer to the parts in the singular, as though the structure lay in a single vertical plane, since the parts of interest do actually lie in substantially such a plane.

In the simple form of short top for roadster type body illustrated in Fig. 1, the top covering 1 is preferably entirely supported through the outrigger structure from a single main bow or standard 2, the latter being pivotally supported on, or attached to, the body of the vehicle at the point 3 in the usual manner, so that it may be laid down and supported in a substantially horizontal plane when the top is not in use. Normally, in the extended or open condition of the top, such main bow 2 inclines rearwardly at an angle approximately 45 degrees to the horizontal, being held from rising further by the top covering, or by special straps, (not shown), or extensions of the longitudinal strainers, which, as is well known, are used to connect the bows together and provide supporting means for the top covering intermediately between said bows. For the purpose in hand such straps or strainers do not require to be distinguished from, but may be regarded as a part of, the covering material.

In the embodiment illustrated in Fig. 1, the outrigger structure comprises a main

articulated auxiliary bow, or, as it is sometimes called, outrigger bow 6, the latter term referring more particularly to the outer portion or bow 7 proper, which is 5 secured by means of an arm 8, (one on each side of course), pivotally attached by means of a suitable clamp or bracket 9 to main bow 2. The joint 10 between the two parts of outrigger or auxiliary bow 6 is a 10 rule joint that locks in the extended position of the top so as to prevent upward bending, and suitable means are provided as usual for tying the outrigger bow 7 proper at its front end to the windshield 11.

15 Pivots attached to arms 8 is a supplemental bow 12 that in the open condition of the top extends forwardly at an acute angle so as to support the top covering 1 intermediately between outrigger bow 7 and 20 main bow 2, the position of said supplemental bow being determined by a stop clamp 13 on each of the arms 8. The lower end 14 of said supplemental bow is projected downwardly beyond the pivot 15 whereby 25 said bow is attached to said arm 8, such end preferably projecting forwardly from the plane of said supplemental bow at such an angle to the bow so as to form, in effect, a short arm of a bell crank, and a link 16 is 30 pivotally attached at its forward end to such bell crank projection 14, and at its rear end to the main bow 2 at a point 17 above the point of attachment of said arm 8 to said main bow.

35 The manner of operation of the top will be readily understood from the indication in dotted outline of the position occupied by the several bows in the folded condition of the top. In other words, upon breaking 40 downwardly the joint 10 the articulated auxiliary or outrigger bow 6 folds up against said main bow, and simultaneously, by reason of the connection of link 16 with the lower end of the supplemental bow 12, 45 the latter is swung into parallelism with the other bows just mentioned, and will lie between the outrigger bow 7 proper and such main bow. The latter may then be dropped down in the horizontal position previously 50 referred to, the latter structure forming a very compact stack, as is highly desirable in tops of the type in hand. In the open condition of the top any downwardly turning moment applied through outrigger bow 7 to 55 swing arm 8 will cause supplemental bow 12 to be pressed against stop 13, the load or pull which is transmitted directly through link 16 to main bow 2 tending to lock said supplemental bow in its limiting position 60 by reason of the location of its point of pivotal connection with bell crank extension 14 relatively to pivot 15, as best shown in Fig. 6, which illustrates specifically the parts in question as embodied in the longer top of 65 Fig. 4.

The construction shown in Fig. 2 is similar in all respects to that shown in Fig. 1, save for the addition of a folding link 18 connecting supplemental bow 12 with outrigger bow 7.

In the modified construction illustrated in Fig. 3 the main bow 20, corresponding with main bow 2, stands approximately upright in the open condition of the top, inclining forwardly just a trifle from the vertical, and the rear portion of the top covering which is sustained by a back bow 21, which is not directly connected with the outrigger structure of present interest. The latter, as before, comprises an articulated auxiliary bow 22 of slightly different form from that shown in Fig. 1, both the outrigger bow 23 proper and the arm 24 being of greater longitudinal extent, and the joint 25 therebetween being prevented from bending upwardly further than desired by direct engagement of supplemental bow 26 with swing arm 28, through the medium of a stop clamp 27 after the fashion described and claimed in United States Patent No. 1,874,627 to C. R. Allen, dated April 12, 1921. Pivots attached to supplemental bow 26 at a point adjacent such stop clamp 27 is a link 28 that corresponds in the disposition of its pivotal connection with link 16 of the top shown in Fig. 1, being likewise attached to the main bow 20 at a point 29 located above the point of attachment of arm 24 to said main bow. The manner in which the parts of the outrigger structure fold up against the main bow 20 is indicated as before in dotted outline, from which the operation of the top as a whole will be readily apparent. As before, the point of pivotal attachment of the link 28 to the supplemental bow 26 is so located with respect to the point of pivotal attachment of said bow to swing arm 24 as to secure the rigid locking effect pointed out in connection with the first described structure.

In Fig. 4 there is illustrated still another modification of the outrigger structure adapting the same for support from a single rearwardly inclining main bow 30, thus eliminating the need of a back bow as in the construction of Fig. 3. However, the articulated auxiliary bow 31 is composed of an outrigger bow 32 proper and a swing arm 33 of still greater longitudinal extent, the joint 34 therebetween being of the same type as is shown in Fig. 1, and the arrangement of the other parts closely corresponding. Thus supplemental bow 35, stop clamp 36 and link 37 are practically identically the same in form and disposition with supplemental bow 12, stop clamp 13 and link 16 of such previously described construction. However, in view of the greater longitudinal extent of the cover 1, it is here desirable to support the same intermediately between outrigger bow 38 and 130

32 and said supplemental bow 35. With this in view a second supplemental bow 38 is provided, being pivotally attached to arm 33 at a point 39 lying approximately midway 5 between the point of attachment of said supplemental bow 35 and the joint 34. A stop 40, corresponding to stop 36, determines the position of said second supplemental bow in the open position of the top, and for the 10 purpose of operatively interconnecting said second supplemental bow with the outrigger bow and first supplemental bow a system of linkage similar to that described and claimed in United States Patent Re. No. 14982 to F. L. Tesmer, dated Nov. 29, 1920, is employed. In other words, a link 41 is pivotally attached at one end to said supplemental bow 38 at the point 42 and at the other end to outrigger bow 32 at point 43 lying beyond 15 the joint 34; while a second link 44 is pivotally attached at its rear end to supplemental bow 35 at a point 45, and at its forward end is connected to said first-named link 41 at a point 46. The manner in which the 20 form of top thus illustrated in Fig. 4 folds up is, as before, indicated in dotted outline, from which it will be seen that despite the increased number of bows involved in the outrigger structure, a compact stack is still 25 obtained. At the same time, in the extended condition of the top the link 37, as before, transmits the load imposed on the arm 33 directly to the main bow by virtue of the 30 positive interlocking action of its connection with supplemental bow 35, to which the outrigger bow and the second supplemental bow are connected through links 41 and 44.

The modification shown in Fig. 5 consists, in effect, in the adaptation of the outrigger structure of Fig. 2 to a top in which the main bow 50 inclines forwardly as in Fig. 3. The parts otherwise, including the folding link between the supplemental and outrigger bows, being substantially identical, are conveniently designated by the same reference 45 numerals as in Fig. 2.

In each of the several modifications of my improved top hereinbefore described it will be noted in the case of the link that connects the main bow or support of the top with the supplemental bow carried by the rear portion of the articulated auxiliary bow that the point of pivotal connection of said

supplemental bow with said auxiliary bow portion lies approximately in line with the 55 ends of said link in the open position of the top or more specifically lies slightly above such line. In other words, the bell crank action and resulting locking effect referred to in the description of Fig. 1 is 60 obtained equally in the case of the several other forms illustrated in the succeeding figures.

Other modes of applying the principle of my invention may be employed instead of 65 the one employed, change being made as regards the mechanism herein disclosed, provided the means stated by any of the following claims or the equivalent of such 70 stated means be employed.

I therefore particularly point out and distinctly claim as my invention:—

1. In a top for vehicles and the like, the combination of a support adapted to be pivotally attached to the body of the vehicle, a forwardly extending auxiliary bow pivotally attached to said support, and adapted to fold thereagainst, a supplemental bow pivotally attached to an upstanding projection on said auxiliary bow, a stop 80 above said auxiliary bow forwardly of such upstanding projection, and a link lying wholly above the normal plane of said auxiliary bow and extending between said supplemental bow at a point forward and below 85 such pivot projection and a point on said support above the attachment of said auxiliary bow thereto.

2. In a top for vehicles and the like, the combination of a support adapted to be 90 pivotally attached to the body of the vehicle, a forwardly extending auxiliary bow pivotally attached to said support, and adapted to fold thereagainst, a supplemental bow pivotally attached to an upstanding 95 projection on said auxiliary bow, and a link lying wholly above the general plane of said auxiliary bow and extending normally at an incline between said supplemental bow at 100 a point forward and below said pivot projection and a point on said support above the attachment of said auxiliary bow thereto.

Signed by me, this 8th day of November, 1921.

SAGITO J. LEACH.
